PHONOGRAPH

Serge Alexander Scherbatskoy, Tulsa, Okla.

Application October 30, 1943, Serial No. 508,357

3 Claims. (Cl. 179—100.4)

This invention relates to phonographic reproduction and more particularly to the picking up and reproducing of oscillations from an undulating record groove. By way of preferred example, the invention has been illustrated and described with reference to grooves undulating laterally, or in the plane of the record surface, but it is to be understood that no unnecessary limitation thereto is intended.

It is an object of the invention to provide a generally improved pick-up device.

It is an object to provide a phonograph apparatus of extreme simplicity, ruggedness and lightness by providing a new type of pick-up device which simplifies considerably the structure of the whole phonograph assembly.

It is an object to provide a pick-up device of extreme simplicity and ruggedness which operates satisfactorily with a very low pressure of its needle or other stylus against the record.

With similar objects in view, a number of pick-up devices of this nature have been used in the past. These may be considered as comprising a moving or "armature" system subjected to vibration by the undulations of the record groove (which will be understood to be moved relatively to the pick-up device), and a translating system responsive to that vibration and serving to translate it into electric oscillations. The translating system may, for example, have a sensitive portion in relatively close spaced relationship to the armature, the vibration of the armature serving to oscillatorily vary this spaced relationship so to influence the translating system. In another view, the translating may have a field, for example electrostatic or electromagnetic, in which the armature vibrates, the resulting oscillatory alteration of the field giving rise to the desired electric oscillations.

The pick-up systems heretofore used were mostly of electrostatic, electromagnetic or piezoelectric type in which the translation of the armature oscillations into electrical current utilized the effects of electrostatic or electromagnetic induction or the piezoelectric effect. It is well known that in the pick-up systems of the prior type the conversion of the mechanical vibrational energy of the pick-up needle into electrical energy took place without the presence of any external sources of energy. Consequently, if we neglect any frictional and eddy current losses, we will realize that the electrical energy derived from the pick-up systems was substantially equal to the mechanical energy of the vibrations of the needle. It is apparent that

5 this electrical energy was too weak to actuate a loudspeaker, and, consequently, in order to provide a successful phonographic reproduction of speech and music, it was necessary to provide electronic amplification in order to intensify the currents derived from the pick-up to a degree required for the operation of a loudspeaker.

Consequently, the phonograph system used in the prior art required an electronic amplifying 10 equipment which rendered the phonographs cumbersome, complicated, and expensive.

It is a purpose of the present invention to provide new phonographic systems in which electronic amplification is eliminated which combine 15 ruggedness and simplicity with low cost and which, therefore, possess considerably increased market possibilities. I am accomplishing this purpose by providing the phonograph with a new pick-up device of electrolytic type in which 20 the conversion from the mechanical, vibrational energy of the needle into electrical energy takes place in presence of a supply of current, such as an electric battery. Consequently, in my new type of pick-up device, the electrical output 25 is considerably larger than the vibrational energy of the needle and may increase at will by increasing the current supply of the battery. Therefore, the electronic amplification is no longer necessary and the whole phonograph assembly 30 is of a considerable simplicity in design.

It is the purpose of my invention to provide 35 a new type of a phonographic pick-up utilizing an electrolyte and two electrodes immersed in the electrolyte and in which the distance between the electrodes is varied by the vibrations of the pick-up needle. Such a pick-up device will be included in a suitable electrical network energized by a source of electrical energy and across the output terminals of the electrical network electrical currents will be obtained which 40 will correspond to the vibrations of the pick-up needle.

It is a further purpose of my invention to 45 provide an improved form of construction of vibrational resistances of the type referred to. This construction relates particularly to vibrational electrolytic resistances in which the distance between the electrodes can be varied when the device is exposed to the vibrations that it 50 is desired to reproduce.

In general, it is an object of my invention to provide a phonographic pick-up device for translating mechanical vibrations into electrical currents which involves the principle of varying the distance between electrodes immersed in

an electrolyte. Such a device may be constructed in an efficient and compact manner similar to well known other pick-up devices for translating mechanical vibrations into electrical currents.

Other objects and advantages of the invention will be apparent from the following descriptions when read in conjunction with the drawing, in which:

Figure 1 is a view, partly elevational and partly cross-sectional, of a pick-up device in which my invention has been embodied together with a schematic diagram of the remaining associated apparatus of the phonograph equipment.

Figure 2 is a cross-sectional view taken along the line 2—2 of Figure 1.

Figure 3 is a cross-sectional view taken along the line 3—3 of Figure 2.

Figure 4 is a cross-sectional view taken along line 4—4 of Figure 2.

Figure 5 shows a modified portion of the phonograph equipment which is energized by a source of alternating current.

Referring now more particularly to Figure 1, there is shown diagrammatically a phonograph system including a pick-up device 10 provided with a vibratable needle 15 subject to vibration of the record groove 17 (which is understood to be moved relatively to the pick-up device). The pick-up device is of a novel type and consists of an electrolytic cell formed by a casing 11, containing a suitable electrolyte 12 and two electrodes submerged in the electrolyte, one of said electrodes being movable and consisting of the needle 15 and the other electrode being stationary and consisting of a metallic spring 16 which shall be referred to later in the description.

The casing 11 may be secured at the front extremity of a cylindrical arm 20 with a slight inclination to bring its bottom somewhat more forward than its top. The arm will be understood to be supported at its rear extremity by a support 19. The support 19 renders the forward extremity of the arm free to move up and down for engagement of the pick-up needle 15 with the record 17, and from side to side so that the needle may track a groove in the record therebeneath.

The output terminals 21, 22 of the pick-up device are connected to an electrical network contained within the block 23 which comprises a source of current 24 energizing the network together with the pick-up device and producing across the output terminals 25, 26 a voltage representing the vibrations of the needle 15 in a considerably intensified form. The output of the network 23 is translated into sound by means of a loudspeaker 30 of a conventional design.

Referring now more particularly to the pick-up device 10, the metallic casing 11 is shown as having a closure member 31 removably secured across its otherwise open bottom. Through the bottom member 31 there is provided a relatively large hole 32; the very top portion 33 of which is made of reduced diameter to provide a shoulder. In the hole 32 there is retained a circular block 35 of resilient material. While this retention may be insured in any desired manner, I have by way of example illustrated the hole 32 as formed with a slight flange 34 inwardly directly at its bottom; the block 35, compressed during insertion to pass the flange, thereafter expands to fill the hole above the flange and to be effectively retained by the latter and secured water-

tight to the closure member 31. Through the resilient block 35, for example centrally thereof, there is provided a very small diameter hole 36.

To the inside of the top of the casing 11 there may be secured a metallic block 37 and in the bottom surface of this block, in line with the hole 36 abovementioned, there may be provided a concave conical bearing 38. The armature system of the pick-up device comprises the needle 15 having the record-contacting point 39 at its bottom extremity and the bearing-contacting point 40 at its top extremity. The needle is simply being pushed upwardly through the hole 36 until its extremity 40 engages the bearing 38. The hole 36 is readily arranged to have a diameter sufficiently small so that the inserted needle will be securely retained water-tight.

It will be understood that the groove undulations in the moving record 17 (with its direction of movement under the needle indicated by the arrow) will cause the needle to vibrate to the right and left—this vibration being permitted by the resilience of the block 35. There will of course be a tendency to similar vibration of the entire pick-up device; but in view of the relatively high inertia of the latter, by far the principal vibration will be of the needle relative to the remainder of the device.

In this vibration the only possible resonance is that of the needle at its own natural frequency (as modified by certain effective parameters of the resilient block 35 in immediate contact therewith). Not only will this frequency inherently be very high, but also the tendency to excessive vibration due to this resonance is effectively damped by the block 35. For this damping action as well as for such damping action as may be desirable on the intended vibration of the needle, it may be desirable to choose the material of the block 35 to have a significant viscous damping, as well as resilient, characteristic. As an example of an appropriate material there may be mentioned the synthetic rubber currently available as "neoprene."

The translating system which I have illustrated is an electrolytic one, basically comprising two electrodes in special relationship one from the other and submerged in an electrolytic solution contained within the casing 11. One of the two electrodes is stationary and consists of the spring 16. The other electrode is the vibratory needle 15 which with the stationary one forms an oscillatorily variable electrolyte resistance. As a mounting for the stationary electrode there may be secured to the inside surface of the righthand side of the casing 11 block 41 of insulating material (such for example as the phenol-resin composition known as "Bakelite"), which may extend very nearly down to the bottom member 31. Just above the bottom of this block 41 there may be provided a horizontal threaded hole 42 extending in a side-to-side direction through the block, and accessible from outside the casing by virtue of an aligned, slightly larger-diameter hole provided in the casing. In this hole 42 whose axis intersects the needle 15 slightly above the resilient block 35 there may be provided an adjustable screw 43. This screw is employed for the adjustment of the stationary electrode 16 which is then made electrically independent of the screw (so that, among other things, touching of the screw with a screwdriver for adjustment purposes will not cause undue electrical disturbances). Accordingly, the stationary electrode has a form of a spring 16 having its upper ex-

tremity secured to the inner surface of the block 41 near the top of the latter, extending therefrom diagonally downwardly and toward the needle, and finally curving into a lower portion essentially parallel to and near the needle. A small pad 45 of insulating material may be secured on the outer side of spring 16 opposite the end of the screw 43, and the spring 16 may be tensioned to maintain contact of this pad against that screw end. It will thus be understood that the screw 43 will serve to adjust the spacing of the operatively stationary electrode or spring 16 from the needle or vibratory electrode 15. In general, this spacing will ordinarily be adjusted to the minimum which still insures failure of contacting of the two electrodes under conditions of maximum vibration of 15.

Preferably the arm 20 will be secured to the casing 11 so that its axis intersects the needle 15. This may be offset (e. g., to the left) from the center of the casing, in view of the space requirement which exists on the one side for the stationary electrode and its support, and which has no counterpart on the other side. Any tendency toward side-to-side unbalance, to such extent as troublesome, may be counteracted by a small weight member such as 46 secured against the inner surface of the lefthand side of the casing 11.

The vibratory electrode 15 is inherently electrically connected with the casing 11 and arm 20, through the bearing member 37 which rests on its upper extremity. Furthermore, the arm 20 is electrically connected through the mounting of the arm 19 to the output terminal 22. For electrical connection to the stationary electrode 16 there may be employed a conductor 47; this may pass longitudinally through the cylindrical arm 20 whose forward extremity preferably is open into the interior of the casing 11. The portion of conductor 47 within the arm may be insulated by the usual insulating covering 48. Further, in order that the capacity between it and the arm may be kept both constant and at a minimum, it is preferable that it be held centrally of the arm by a packing 49 of suitable insulating fibrous material or the like.

In considering the action of the structure of the electrolytic pick-up it is convenient to bear in mind that the efficiency of the translating system and action is dependent on the spacing of the armature or needle 15 from the stationary electrode or spring 16 and upon the electrolyte resistance of the liquid in which both electrodes are submerged. It is well known that the electrolytic resistance between the electrodes depends upon the resistivity of the electrolyte which is a function of factors such as the nature of the electrolyte, its concentration, etc., and also depends upon the distance between the electrodes. Consequently under the aforementioned conditions when no vibrations are present the electrolyte resistance between the electrodes 15 and 16 has a fixed and determined value, because the distance between the electrodes 14 and 16 is fixed and determined.

It will be understood that as the armature or needle 15 is vibrated by the groove undulations, the distance between the needle 15 and the spring 16 will vary, and will cause variations in the electrolytic resistance between needle and the spring. Consequently, changes in electrolytic resistance between the connecting leads 21 and 22 will be produced when the needle 15 becomes subjected

to vibrations by the undulations of the record groove.

The output leads 21 and 22 of the pick-up device are connected to a Wheatstone bridge circuit 50 which is energized by a D. C. source of voltage, which is represented by a battery 24. One arm of the Wheatstone bridge consists of the electrolytic resistance inserted between the leads 21, 22, and the remaining three arms of the bridge circuit consists of resistors 56, 57, and 58.

The battery 24 is applied between the terminals 60 and 61, the terminal 60 being the point of junction of the resistor 56 and the lead 22 and the terminal 61 being the point of junction of the resistors 57 and 58. The resistors 56, 57, and 58 have been so chosen that when the needle 15 is at rest the ratio of the resistance 58 to the resistance 57 is equal to the ratio of the electrolytic resistance to the resistance 56. It can readily be shown that the bridge is "balanced," that is, the potential difference resulting from the source 24 and applied across the terminals 60 and 61 will cause no potential difference to exist between terminals 70 and 71, the terminal 70 being the point of junction of the resistor 58 and of the lead 21, and the terminal 71 being the point of junction of the resistors 56 and 57. The terminals 70 and 71 are connected through the leads 25, 26 to the loudspeaker 30.

It will be understood that the groove undulations in the moving record will cause the distance between the needle 15 and the spring 16 to alternately decrease and increase. When the distance decreases, the bridge 50 becomes unbalanced and a D. C. voltage appears across the output leads 25 and 26. It can be readily appreciated that the magnitude of this voltage represents the degree of unbalance of the bridge. Consequently, when distance between the needle 15 and the spring 16 continues to decrease the unbalance of the bridge continues and the voltage across the output leads 25, 26 becomes larger. When, however, the deviation of the needle has attained a minimum and then increases by passing through the normal equilibrium position, the voltage across the output leads 25, 26 decreases and reaches the value zero. It is readily apparent that when the needle deviates in the opposite direction, the unbalance voltage across the output leads 25 and 26 appears again with a polarity which is opposite to the one referred to above. Consequently, the polarity of the unbalance voltage appearing across the output leads 25 and 26 represents the left or right deviation of the needle and the magnitude of the voltage represents the magnitude of the deviation.

It is, therefore, apparent that across the output leads 25 and 26, we obtain electrical oscillations which represent mechanical vibrations to which the needle 15 is subjected by the undulations of the record groove. These oscillations are subsequently impressed to the loudspeaker 30 which therefore reproduces speech or music or any other vibrations impressed upon the record

17.

We shall consider now the most suitable electrolytes that may be used in order to provide a variable D. C. resistance. Electrolytic resistors of many types and kinds have been made in the past, but most of them were subject to limitations of polarization, gassing, non-uniformity or lack of permanence. The use of electrolytic resistors has been confined therefore to applications in which these detrimental features were not objectionable or for which they possessed

some positive advantages. Because of polarization and gassing when used with direct currents, electrolytic resistors are more generally associated with A. C. circuits. However, certain types may be used successfully in D. C. circuits.

The polarization is due to the fact that a counter E. M. F. is effective on the electrodes owing to the formation of an oxy-hydrogen element. This counter E. M. F. must be annulled by removing immediately the oxygen when being formed on the electrode. This is possible by reducing the separated oxygen with the aid of hydrogen.

Accordingly, in the present application the polarization is absolutely eliminated by the fact that at least one electrode on which oxygen would deposit or both electrodes, during the passage of the electric current, are brought into contact with a substance which possesses a hydrogen pressure sufficient to reduce the oxygen depositing on either electrode.

All solid or liquid substances having any partial pressure of the hydrogen are, therefore, suitable for the elimination of the polarization effect; however, such substances are preferably employed which do not cause any ionic reactions affecting the conductivity that is to say, substances of neutral molecules having a certain partial pressure of the hydrogen, such as for instance, quinhydrone. Besides, all reduction-oxidation systems which present a partial pressure of the hydrogen are suitable for this purpose such as, for instance, indophenol, methylene blue, etc.

Furthermore, electrolytes may be employed such as an aqueous solution of a mixture of FeCl_3 and FeCl_2 . Since only very small quantities are, as a rule, necessary for the reduction of the oxygen, they can be so arranged that the conductivity caused by the addition of such electrolytes may be practically neglected with respect to the conductivity to be measured.

In practice, it has been found that slight traces of quinhydrone which are added to the solution under test, prevent completely polarization when using platinum electrodes. For instance, an amount less than 1 mg. substance is sufficient for one liter of solution. Instead of platinum, also less noble metals, such as gold, silver, iron-nickel alloys, etc. may be employed as substances for electrodes which absorb the oxygen depositing on the electrode in such a manner that the oxygen reacts with the hydrogen of the material added thereto.

The electrolyte to be used in the electrolytic pick-up may also be of the type described in Research paper R. P. 1126, part of the Journal of Research of the National Bureau of Standards, vol. 21 (August 28, 1938), which is used in combination with copper electrodes and consists essentially of a mixture of approximately 1 part 36% aqueous solution 1 hydrochloric acid, $\frac{1}{8}$ to 4 parts ethyl alcohol and about $2\frac{1}{2}$ grams per 100 ml. of cuprous chloride.

Instead of employing electrodes and an electrolyte which undergo no change in their chemical constitution by the passage of the current, electrodes and an electrolyte in which such change does occur may be employed, but in this case it is desirable to select the electrolyte and the electrodes so that the chemical changes are reversible, whereby permanent change in the chemical constitution can be prevented by reversing the direction of current flow at a certain selected rate. Such an arrangement is illustrated in Fig. 5 which represents a network to be

connected to the output leads 21, 22 of the pick-up device 10 and to be energized by an A. C. source 144. The network shown in Fig. 4 has its output leads 25, 26 connected to the loudspeaker 30 and is designed to substitute the network 23 in the phonograph assembly shown in Fig. 1.

The electrolyte contained in the pick-up used with the network of Fig. 5 may consist of copper sulphate and the electrodes of copper plates or of mercury nitrate with mercury electrodes, or any other suitable combination of electrolyte and electrodes.

The network shown in Fig. 5 includes a Wheatstone bridge 140, the three arms of which are made up by resistors 141, 142, and 143, and the fourth arm of which is constituted by the electrolytic resistance of the pick-up inserted between the leads 21 and 22. The bridge is supplied with an A. C. current by means of a source 144 having a frequency f .

It is apparent that when the needle 15 occupies a neutral position the voltage across the output terminals of the bridge 140 is zero. Whenever, the needle 15 deviates from its neutral position, there appears a voltage across the output terminals of the bridge, the frequency of which is f and the amplitude of which is proportional to the amount of the displacement of the needle. Consequently, when the displacement of the needle continuously varies due to the vibratory motion, the unbalance voltage appearing across the output terminals of the bridge 140 is being represented by a modulated carrier, the frequency of the carrier being the same as that of the source 144 and the modulation varying in accordance with the vibration of the needle 15. It is desired to reproduce the vibration of the needle and I am accomplishing this by demodulating the unbalance voltage derived from the Wheatstone bridge. Thus, the instantaneous value of such a demodulated voltage will represent at any instant the magnitude of the displacement of the needle 15 from its neutral position and the polarity of this voltage will indicate at any instance whether or not the impressed displacement has been effected in the right or in the left direction. In order to accomplish this purpose, I am applying the output terminals of the bridge 140 to a ring modulator contained within the dotted rectangle 160. The ring modulator 160 is provided with two pairs of input terminals 147a, 147b, and 175a, 175b, respectively, and one pair of output terminals 25 and 26. The input terminals 147a and 147b are connected to the output of the bridge 140, the input terminals 175a, 175b receive the output from the source of voltage 144, and the output terminals 25, 26 are connected to the loudspeaker 30.

The ring modulator is well known in the art and has been described in an article by R. S. Carruthers on "Copper oxide modulators in carrier telephone systems," the Bell System Technical Journal, vol. XVII, 1939, pp. 315-337. The type of the circuit contained in the dotted rectangle 160 is illustrated in Fig. 2c, page 318 of the said article. The ring modulator is essentially a double balanced modulator. By double balanced is meant a modulator in which each input is balanced out from the output, and the output contains therefore substantially only the modulation products.

Consider now the ring modulator circuit contained in the rectangle 160. The circuit shown therein comprises a bridge circuit consisting of

four rectifiers 181, 182, 183, 184 each of the said rectifiers constituting a separate arm of the bridge circuit and arranged so that the current can flow only in an anticlockwise direction. The upper corner of the bridge 185 and the lower corner of the bridge 186 are respectively connected to the input terminals 147a, 147b and are also connected one to another by means of equal resistances 187 and 188 in series. The other corners of the bridge 189 and 190 are respectively connected to the output terminals 25, 26 and are also connected one to another by a pair of equal resistances 191, 192 in series. The other input terminals 175a, 175b of the ring modulator are respectively connected to the point 193 connecting the resistances 187, 188 and to the point 194 connecting the resistances 191, 192.

With the circuit as described, current derived from the terminals 147a, 147b may flow either through the rectifiers 182, 183 or through the rectifiers 184, 181 depending upon its direction, but it can never flow through all the four rectifiers at the same time, since the rectifiers 182, 183 on one hand and the rectifiers 184, 181 on the other hand are arranged to flow in opposite directions.

Suppose now for purpose of illustration that the voltage derived from the terminals 175a, 175b and the unbalance voltage derived from the terminals 147a, 147b are simultaneously applied, and suppose that both voltages are in phase, i. e., the terminal 147a becomes positive as compared to the terminal 147b and at the same time, the terminal 175a becomes positive as compared to the terminal 175b. Then one part of the current tends to flow from the terminal 175a to the terminal 193 and through the resistor 187 to the terminal 185 and then through the rectifier 182 and through the resistor 191 back to the terminal 175b. The other part of the current tends to flow from the terminal 175a to the terminal 193 and through the resistor 188 back to the terminal 186 and through the rectifier 184 and through the resistor 192 back to the terminal 175b. The currents flowing through the resistors 191, 192 are equal and of opposite directions.

It is apparent that under the conditions described in the preceding paragraph, the polarity of the terminals 185, 186 will be positive with respect to the polarity of the terminals 189, 190. Consequently, positive voltages are applied to rectifiers 182, 184. Therefore, these rectifiers will lose their ability of rectifying currents, and will allow currents to traverse them in both directions. At the same time negative voltages are applied to rectifiers 181, 183. Consequently, the rectifiers 181, 183 will retain their rectifying ability and will block currents attempting to traverse them in the negative direction. Therefore, the rectifiers 182 and 184 are conductive in both directions and consequently, when the unbalance voltage is being developed across the terminals 147a, 147b, we find that a current tends to pass from the terminal 147a to the terminal 185 and then through the rectifier 182 through the resistors 191 and 192 to the terminal 190, then through the rectifier 184 back to the terminal 147b. This current superposes itself upon the current which is already flowing through the resistors 191 and 192 and consequently, the resultant current passing through the resistor 191 becomes larger than the current passing through the resistor 192. Consequently, the balancing that existed before is offset because there is a situation where the current flow through the

resistor 191 is increased as compared to the current flow through the resistor 192. Thus, the voltage drop across the resistor 191 becomes greater and a positive overall voltage is developed across the terminals 25, 26. It can be also readily seen that when the unbalance voltage applied across the terminals 147a, 147b increases in magnitude the corresponding resultant voltage obtained across the output terminals 25, 26 increases in magnitude also.

It can be shown that if the polarity of the first input voltage would reverse with respect to the second input voltage, i. e., if we suppose that the terminal 175a becomes positive as compared to the terminal 175b and the terminal 147a becomes negative as compared to the terminal 147b, then the balance becomes offset in the opposite direction, because there is a situation where the current flow through the resistor 191 is decreased as compared to the current flow through the resistor 192. Then the voltage drop across the resistor 191 becomes smaller and the overall voltage developed across the output terminals 25, 26 has a polarity opposite to the case described above.

It can also be shown that in an intermediate situation where the signal voltage derived from the input terminals 175a, 175b is displaced by 90 degrees with respect to the voltage derived from the input terminals 147a, 147b then the D. C. voltage output from ring modulator is zero.

Let us designate the voltage applied across the terminals 175a, 175b as $E \sin 2\pi ft$. Then the unbalance voltage derived from the Wheatstone bridge and applied across the terminals 147a, 147b can be represented by a carrier of the frequency f , modulated by the vibration of the needle 15 according to a function $A(t)$ which represents the variation of the instantaneous displacement of the needle 15 with respect to its neutral position. Consequently, the unbalance voltage applied to the terminals 147a, 147b can be represented by the following expression: $A(t) \sin 2\pi ft$. It can be readily appreciated that under these conditions the voltage derived from the output terminals 25, 26 of the ring modulator varies with time as the function $A(t)$, i. e., this voltage represents the vibration of the needle. The voltage derived from the ring modulator is subsequently applied to the loudspeaker 30 in which the vibrations of the needle are being reproduced.

I claim:

1. In a phonographic pick-up device, adapted for the translation of mechanical oscillations from the undulating groove of a moving record into corresponding electrical oscillations and including vibration translating means: the combination of a stylus adapted to engage in and to be vibrated by the groove of said record and to influence the translating means, the translating means comprising a vessel containing electrically conductive fluid with electrodes immersed in said fluid, and means responsive to the vibrations of said stylus for varying the relative position of said electrodes as a function of said vibrations whereby the resistance of said fluid between said electrodes varies, an electric network connected to said electrodes and a source of voltage connected to said network whereby the variation of said resistance between said electrodes produces electrical oscillations in the output of said network, said oscillations representing the undulations in the groove of said moving record.

2. In a phonographic pick-up device, adapted for the translation of mechanical oscillations from the undulating groove of a moving record

into corresponding electrical oscillations and including vibration translating means: the combination of a stylus adapted to engage in and to be vibrated by the groove of said record and to influence the translating means, the translating means comprising a vessel containing electrically conductive liquid with metallic electrodes immersed in said liquid, said liquid comprising in solution a substance having in its chemical composition the same metal as that of which one of said electrodes consists, and means responsive to the vibrations of said stylus for varying the relative position of said electrodes as a function of said vibrations whereby the resistance of said liquid between said electrodes varies, an electric network connected to said electrodes and a source of voltage connected to said network whereby the variation of said resistance between said electrodes produces electrical oscillations in the output of said network, said oscillations representing the undulations in the groove of said moving record.

3. In a phonographic pick-up device, adapted for the translation of mechanical oscillations from the undulating groove of a moving record into corresponding electrical oscillations and including vibration translating means: the combi-

nation of a stylus adapted to engage in and to be vibrated by the groove of said record and to influence the translating means, the translating means comprising a vessel containing a conductive fluid, electrodes immersed in said fluid in a determined spaced relationship one from the other, whereby the resistance between said electrodes has a determined value corresponding to said relationship, electric circuit elements connected to said electrodes to form a bridge network, a supply of current connected to said network for energizing said network, the values of said circuit elements being such as to balance said network for said determined spaced relationship between said electrodes and thereby produce no voltage in the output of said network, means responsive to the vibrations of said stylus for varying the relative position of said electrodes as a function of said movements whereby the resistance between said electrodes varies and causes an unbalance of said network, thereby producing in the output of said network a voltage representing said unbalance and varying as a function of the vibrations of said stylus, said voltage representing the undulations in the groove of said moving record.

SERGE ALEXANDER SCHERBATSKOY.
